UNITED STATES PATENT OFFICE.

LORETO ALONZI, OF CHICAGO, ILLINOIS.

TEA TABLE.

Application filed January 8, 1923. Serial No. 611,245.

To all whom it may concern:

Be it known that I, LORETO ALONZI, a citizen of the United States, and resident of Chicago, in the county of Cook and State of Illinois, have invented certain new and useful Improvements in a Tea Table, of which the following is a specification.

My invention relates to furniture and particularly to a novel tea table construction in which a disappearing handle or pull is provided.

It is customary in the construction of tables of the character described to provide casters at one end and at the opposite end a handle so arranged that the end may be lifted and the table moved from place to place on the two casters. The device of my invention comprises means adapting the table for a plurality of uses other than that for which it is primarily intended. For example, in the absence of a projecting handle or pull, the table may be employed for games of cards or for a breakfast table. To that end I have illustrated a construction in which the operating handle may be caused to disappear underneath the top when not required for use. When required, the part may be withdrawn and automatically interlocked with the table by a simple outward pull thereon. When not required the action of depressing the handle enables it to be retracted through the action of a spring. I am aware that disappearing handles have heretofore been suggested. However my improvement relates to features of construction which render the device more practical in use and operation.

The invention will be more readily understood by reference to the accompanying drawing, wherein:

Figure 1 is a side elevation partly in section of a table constructed in accordance with my invention, the handle being shown in full lines in retracted position and in dotted lines in extended position;

Figure 2 is a bottom plan view; and

Figure 3 is an end elevation partly in section.

In the drawings I have illustrated a table of well-known construction comprising legs 10, side frames 11 and a top 12. Caster wheels 13 may be provided at one end of the table. The disappearing handle comprises a rigid rectangular frame consisting of side pieces 14, a cross piece 15, and a rounded handle portion 16. The side pieces are

shaped as best shown in Figure 1 and extend through openings 17 in the side frames 11. The cross piece rigidly connects the side pieces and is located underneath the top, constituting the stop for limiting the outward withdrawal of the arms constituting the side pieces. Strips 21 having a notch 14^a in their upper surface are secured to the sides by means of nails or screws indicated at 23 in Figure 2, these strips forming guideways and supporting the side pieces 14. The pointed ends 18 of the side pieces cooperate with the notch 14^a in the side pieces as shown in dotted lines in Figure 1, such means constituting an interlock for the handle when in exposed position. A spring 19 is connected at one end to the center of the cross piece 15 and at the other end to a block 20 secured to the underside of the table. This serves to normally retract the handle portion when it is released from its extended position. It will be noted that the spring is so connected that it exerts a downward as well as an inward pull on the parts and this serves to retain the handle in the exposed position.

In practice with the parts in the position shown in full lines in Figure 1, the user will grasp the handle portion 16 at the center and withdraw it against the force of the spring 19. When the proper point is reached the pointed ends 18 will drop into the notches 14^a in the side pieces and the handle will remain as long as desired in the dotted line position shown in Figure 1. When it is no longer desired that the part should project, a simple downward pressure on the part 16 will rock the connected parts sufficiently to lift the pointed ends out of the notch and the spring will cause the handle to be retracted. While the upper edges of the side pieces are shaped to substantially conform to the shape of the edge of the table top, the parts are preferably out of contact at that point in order to avoid marring the top.

Obviously the construction is capable of much modification and I do not wish to be limited except as indicated in the appended claims.

I claim:

1. In a table, the combination with the legs and top, of a pull therefor, said pull comprising a rigid rectangular structure consisting of notched side-pieces, and connecting members one of which is shaped to be grasped by the user, the table being pro-

vided with notched slide-ways within which said side pieces may be reciprocated, and means on the side pieces for engaging the notches in the slide-ways for interlocking therewith.

2. In a table, the combination with the legs, apertured frame and top of a disappearing handle adapted for sliding movement in a horizontal plane comprising a pull and side pieces projecting through the apertures in said frame, guide pieces secured to the inside surface of said frames, and a spring for retracting said parts.

3. In a table, the combination with the legs, apertured frame and top of a disappearing handle adapted for sliding movement in a horizontal plane comprising a pull and side pieces projecting through the apertures in said frame, guide pieces secured to the inside surface of said frames, and means on the side pieces for interlocking with the guide pieces when the handle is in exposed position.

4. In a table, the combination with the

legs, apertured frame and top of a disappearing handle comprising a pull and side pieces projecting through the apertures in said frame, guide pieces secured to the inside surface of said frames, means on the side pieces for interlocking with the guide pieces when the handle is in exposed position, and spring means for retracting the parts to unexposed position when the interlock is released.

5. In a table, a disappearing pull, consisting of a rigid rectangular frame including two side pieces and two cross-pieces, the outer one of which acts as a handle, said side pieces having their inner ends pointed, the table having notched slide-ways adapted to guide the side pieces and to interlock therewith in one position of the parts, and a spring mounted to exert an inward and downward force, the downward force urging the parts into interlocked position.

Signed at Chicago, Illinois, this 4th day of January, 1923.

LORETO ALONZI.
